UNITED STATES PATENT OFFICE.

ROBERT L. WATKINS, OF NEW YORK, N. Y.

RHEOSTAT.

1,082,982.

Specification of Letters Patent.

Patented Dec. 30, 1913.

Application filed May 22, 1911. Serial No. 628,660.

To all whom it may concern:

Be it known that I, ROBERT L. WATKINS, a citizen of the United States, and a resident of the borough of Manhattan, in the city, county, and State of New York, United States of America, have invented certain new and useful Improvements in Rheostats, of which the following is a specification.

My invention relates to rheostats, and its 10 object is to provide a compact portable device of simple, light, and strong construction which shall have advantages over those heretofore in use.

To these ends I have invented the construction and arrangement of parts which I will describe in the following specification, and the novel features of which I will set forth in the appended claims.

Referring to the drawings, Figure 1 is a 20 plan view of a preferred form of my invention, in its folded condition, and Fig. 2 is a plan view of the same unfolded or open. Fig. 3 is a side elevation of the folded device with one of the covers broken away and 25 removed. In Fig. 4 I have shown a detail of construction, this figure being a plan view of the end of one of the resistance elements or leaves, as I shall call them, together with the collar and lug to which it is affixed. Fig. 5 shows the contact pins which are used 30 with this device. Fig. 6 is a side elevation of another form of the rheostat which I have invented. Figs. 7 and 8 are a rear elevation and a plan view, respectively, of the device 35 shown in Fig. 6. Fig. 9 is a rear elevation of another modified structure embodying my invention. This is shown in side elevation with the top cover removed, in Fig. 10, and in plan view in Fig. 11.

40 Like characters of reference designate corresponding parts in all of the figures.

10 designates a resistance element or leaf which comprises a thin body or sheet 11 of some suitable insulating material, preferably 45 mica. Supported upon opposite sides of this sheet and lying flat against the surfaces thereof are the convolutions of a continuous resistance wire 12. This may be threaded through holes 13 drilled through the mica to receive it, as shown in Figs. 3 and 8, or may be wound around in notches 13^A in the edge of the mica and held in place thereby as shown in Fig. 10; or a combination of holes and notches may be used. At 50 any rate, the wire is usually of small gage, and it is important that it is permanently

held in place so that adjacent parts of it cannot come in contact with each other, and so that it may not slip out of place when it is expanded by heat.

Over one edge of each leaf are bent two copper or other metallic strips 14 and 15 which are separated from each other. The opposite ends of the resistance wires are connected with these strips. To each strip is 60 connected a boss or collar such as 20, through the center of which is bored a hole 21. In Figs. 1 and 2 five of these leaves 10, 10^A, 10^B, 10^C, and 10^D are shown, and from these figures it may be seen that they 65 are offset from a line drawn through the center of the hole 21 and parallel with the folded leaves, and that the offset of all of the leaves is different. 22 and 23 designate covers for this device. These covers may 70 be made of plain sheets of mica bound on all four sides by strips of copper 24. Affixed to this binding on the inner edge are collars such as 20, and these covers are also offset from the collars. A pin 25 runs through 75 the holes in all of the collars, and hinges the covers and the resistance leaves together. Surrounding this pin is a sleeve 26 of insulation. The lower end 27 of the pin preferably projects below the lower collar 80 so that it may be inserted in a hole in a table, box, or pedestal to hold the device 85 in an upright position.

In order to more clearly specify the construction of the device I will further point 90 out that all of the collars 20 are in different horizontal planes as is shown in Fig. 3. In this figure the cover 22 is connected to collars 20^A and 20^B. The resistance leaf 10 is connected with collars 20^C and 20^D, 95 the leaf 10^A to collars 20^E and 20^F, and so on down to collars 20^G and 20^H to which the cover 23 is attached. Between the collars, above the top one, and below the bottom one are bushings 28 of insulation.

100 From each collar 20 projects a lug 30 in which is a hole 31, and these lugs are cut through or split as is shown at 32. These lugs all project in different directions of angularity as is shown in Figs. 1 and 3. 105 These directions of angularity are so related to each other that when the device is opened, as is shown in Fig. 2, all of the upper lugs—one of which is connected with the cover 22, and the others to the copper strips 14 of 110 the resistance leaves—are in alinement with each other; and the lower lugs are also in

alinement with each other in a different angular position. Also, these lugs are so placed that when they are thus in alinement the covers and the resistance leaves will be spaced apart equally.

33 is a contact pin of slightly larger diameter than that of the holes 31. A conductor 34 is affixed to it. This pin is arranged to be thrust down through all of the holes 31 in the lower set of lugs. The fact that these lugs are split allows for this and also insures a good electrical connection between the conductor 34 and the copper strips 15, and one of the ends of each of the resistance wires.

15 35 is another contact pin to which a conductor 36 is attached. This is arranged to be thrust through two or more of the upper lugs, and if desired, a screw 37 may be provided to hold it in place. If this pin is 20 thrust through only two of the lugs, that is, the cover lug 20^A and the upper lug 20^C of the resistance leaf 10, this one resistance leaf will be included in the circuit between the conductors 34 and 36. By pushing pin 25 35 down through another lug 20^E, another resistance leaf 10^A will be included in the circuit in parallel with the resistance leaf 10. Similarly, three, four or all of the resistance leaves may be included in the circuit.

The resistance wires 12 are preferably so proportioned that they have an equal resistance, so that each will permit a passage of the same amount of current; for 35 example, the resistance wire of each leaf may be of such dimensions as to allow the passage of one ampere on a 110 volt circuit. Then, by adjusting the position of the pin 35, the rheostat may be made to 40 allow one, two, three, four or five amperes to pass. Of course, more or less than five resistance leaves may be provided.

Among other advantages of this device are that it affords large radiating surfaces 45 spaced apart to give ample ventilation, and when folded it may be easily carried in the pocket. The resistance leaves are protected by the covers especially when folded.

The device shown in Figs. 6, 7 and 8 embodies some of the novel features of the form of my invention which has been already described. In these figures the resistance leaves of mica or other suitable sheet-like insulating material are designated by 40, 40^A, 40^B and 40^C. Each of these is provided with rows of small holes 13 through which the continuous resistance wire 12 is threaded. Over one edge of each sheet are folded metallic strips 41, 42, separated from each other, to which the ends of the resistance wire 12 are connected. Over the other three edges of each leaf is folded a metallic binding 43, similar to the binding 24, which is over the four edges of the covers 60 22, 23 in the device shown in Figs. 1 and 2.

These bindings stiffen the structure and protect it from mechanical injury. Binding screws 44, 45 pass through holes in the strips 41, 42 and in the mica, and through other metallic blocks 46, preferably rectangular in shape. On the ends of these screws are nuts 47, 48. Thus the leaves are rigidly held in parallelism with air spaces between them. They are also electrically connected as one of the ends of each resistance wire is 70 connected with the screw 44 and the opposite end of each wire is connected with the screw 45. A greater or lesser number of resistance leaves may thus be built up to make a rheostat of desired resistance and one in which the carrying capacity increases as its resistance decreases.

15 The other modification which is shown in Figs. 9, 10 and 11 is somewhat similar. But in this case each resistance leaf, such as 50, is constructed of two sheets of mica 51, 52 placed side by side with notches or side openings 13^A cut in the longitudinal edges thereof. Over one of the transverse edges of each sheet are bent metallic lugs 53, 54, and between them and separated therefrom is a metallic strip 55 which holds the two sheets of each leaf together. A similar strip 56 is bent over the opposite end of each leaf for the same purpose.

20 The resistance wire 12^A is connected with the lug 53 and is wound around the sheet 51 in the notches 13^A therein. Then it is carried down to sheet 52 and is wound around it in its notches back to the lug 54 to which 90 it is connected.

25 57 and 58 are clamps which hold the leaves together by means of screws in one side thereof. Metallic blocks 59 are interposed between the lugs 53, 54 in line with the 105 clamp screws. These space the leaves apart and connect adjacent ends of the resistance wires together electrically. A supporting bar 60 is connected with each of these clamps 57 and 58 but is insulated therefrom. One 110 end 61 of this bar projects to one side of the device and may be threaded as shown. By means of this projecting end the device may be supported.

30 63, 63 are mica covers held over the sides of this device by wires 64.

What I claim is.—

1. A folding rheostat comprising a plurality of resistance leaves, a pair of collars for each of the leaves, a pivot passing 120 through all of the collars, and a pair of contact pins, one of said pins being arranged to be thrust through portions of one of each pair of collars, and the other pin arranged to be thrust through portions of a desired 125 number of the other ones of said pairs of collars.

2. A folding rheostat comprising a plurality of resistance leaves, each leaf having a sheet-like body of insulation and the re- 130

- sistance material wound about said body, a pair of collars for each of the leaves in axial alinement with one another, a pivot passing through all the collars, said leaves being off-
 5 set from one another by varying amounts; and a pair of contact pins, one of said pins being arranged to be thrust through portions of one of each pair of collars to hold said leaves apart and the other pin arranged to be thrust through portions of a desired number of the other ones of said pairs of collars. 10
3. A folding rheostat comprising a plurality of resistance leaves, each leaf having a sheet of mica with openings therein, and a resistance wire wound about said sheet through the openings, a pair of collars for each of the leaves in axial alinement with one another, the ends of each resistance wire being connected to the collars of its resistance sheet, a pivot passing through all of the collars, means for insulating the pivot from the collars; and a pair of contact pins, one of said pins being arranged to be thrust through portions of one of each pair of collars to hold said leaves apart, and the other pin arranged to be thrust through portions of a desired number of the other ones of said pairs of collars, the pins being arranged to electrically connect the resistance wires together. 20
4. A folding rheostat comprising a plurality of resistance leaves, each leaf having a sheet of mica with openings therein, a resistance wire wound about each sheet through said openings, a pair of covers of insulating material; a pair of collars for each of the leaves and the covers in axial alinement with one another, a pivot passing through all of the collars, means for insulating said pin from the collars, and means for insulating the collars from one another, said pivot being elongated to support the rheostat; and a pair of contact pins, one of said pins being arranged to be thrust through portions of one of each pair of collars to hold said leaves apart, and the other
- pin arranged to be thrust through portions of a desired number of the other ones of said pairs of collars, the pins being arranged to electrically connect the resistance wires together. 50
5. A folding rheostat comprising a plurality of resistance leaves, collars affixed to said leaves in axial alinement with one another, a pivot through the collars, lugs projecting from the collars in different angular directions, said lugs being arranged to be moved into alinement with each other when the leaves are spread apart, and a contact pin arranged to be thrust through said lugs. 55
6. A folding rheostat comprising a plurality of resistance leaves, a pair of collars affixed to each of said leaves in axial alinement with one another, a pivot through the collars, lugs projecting from the collars in different angular directions, said lugs being arranged to be moved into two axial lines when the leaves are spread apart, and a pair of contact pins arranged to be thrust through said lugs. 60
7. A folding rheostat comprising a plurality of resistance leaves, resistance wires thereon, a pair of collars affixed to each of said leaves in axial alinement with one another, a pivot through the collars, connections between the ends of the resistance wires and the collars on their respective sheets, lugs projecting from the collars in different angular directions, said lugs being arranged to be moved into two axial lines when the leaves are spread apart, and a pair of contact pins arranged to be thrust through said lugs to hold the sheets apart and to connect a desired number of the resistance wires together in parallel. 70
8. A folding rheostat comprising a plurality of resistance leaves, a pair of collars affixed to each of said leaves in axial alinement with one another, a pivot through the collars, lugs projecting from the collars in different angular directions, said lugs being arranged to be moved into two axial lines when the leaves are spread apart, and a pair of contact pins arranged to be thrust through said lugs to hold the sheets apart and to connect a desired number of the resistance wires together in parallel. 75
9. A folding rheostat comprising a plurality of resistance leaves, resistance wires thereon, a pair of collars affixed to each of said leaves in axial alinement with one another, a pivot through the collars, connections between the ends of the resistance wires and the collars on their respective sheets, lugs projecting from the collars in different angular directions, said lugs being arranged to be moved into two axial lines when the leaves are spread apart, and a pair of contact pins arranged to be thrust through said lugs to hold the sheets apart and to connect a desired number of the resistance wires together in parallel. 80
10. A folding rheostat comprising a plurality of resistance leaves, resistance wires thereon, a pair of collars affixed to each of said leaves in axial alinement with one another, a pivot through the collars, connections between the ends of the resistance wires and the collars on their respective sheets, lugs projecting from the collars in different angular directions, said lugs being arranged to be moved into two axial lines when the leaves are spread apart, and a pair of contact pins arranged to be thrust through said lugs to hold the sheets apart and to connect a desired number of the resistance wires together in parallel. 85

In testimony whereof I have signed my name to this specification in the presence of two subscribing witnesses.

ROBERT L. WATKINS.
